WRITING INSTRUMENT

Ellery A. Boss, Edgewood, R. I., assignor to A. T. Cross
Pencil Company, a corporation of Rhode Island

Application January 19, 1954, Serial No. 404,835

5 Claims. (Cl. 120—42.03)

This invention relates to a writing instrument and more particularly to the mechanical mechanism used to extract a marking device.

An object of the invention is to improve upon the construction of writing instruments, particularly by the reduction in the diameter thereof.

Another object of the invention is to provide a writing instrument which is adapted to extract and retract a ball point pen cartridge which is removably received in one part thereof.

A more specific object of the invention is to provide in a writing instrument a central tube in two sections that slide relative to each other, one of said parts having driving tension applied to it, the other of said parts being driven for rotation.

With these and other objects in view, the invention consists of certain novel features of construction as will be more fully described and particularly pointed out in the appended claims.

In the accompanying drawings:

Figure 1 is a sectional view taken through the body of the writing instrument;

Figure 2 is an exploded view showing the sliding engagement of the upper section of the central tube with the lower section thereof;

Figure 3 is a perspective view of the outer engaging sleeve; and Figure 4 is an enlarged partial sectional view taken through the body of the writing instrument showing the sliding joint between the two sections of the central tube and the driving helix.

In proceeding with the invention, I provide an outer casing and mount therein a central tube with a lower section to which there is attached a point assembly having a bore therethrough. Surrounding this lower section there is slidably received a boss and a helical spring tensioning device extending between the boss and an abutment on the lower section, the upper end thereof being provided with a hexagonal female socket which is adapted to receive a hexagonal male plug of the upper section of the central tube. The upper section carries the ball point cartridge and has a helical recess along a portion thereof. Surrounding this entire assembly and extending from the boss on the lower section is an external sleeve that is provided with helical projections adapted to engage the helical recesses in the upper section.

Referring to the drawings, the writing instrument is provided with a casing 10 which encloses the extracting mechanism and is provided with an upper portion 11 of the same diameter thereof which forms a cap, a clip 12 being fastened to the upper portion 11 so as to retain the instrument in the owner's pocket. Within the lower end of the casing 10 there is provided a point bushing 13 having a bore therethrough, the bore being adapted to frictionally engage and hold the lower section 14 of a central tube. Surrounding the lower section 14 is a boss 15 which is adapted to rotate thereon. Spaced from the boss 15 is a washer 16 that is held in position on the section 14 by a dimple 17, and extending between

2

the boss and washer 16 is a helical flat spring 18 which provides a longitudinal tension between the bushing 13 and washer 16. Non-metallic washers 19 and 20 encircle tube section 14 between boss 15 and bushing 13 and are provided to prevent the rubbing of metal to metal parts. The lower end of the bore in bushing 13 is threaded as at 21 and is adapted to receive a finished point 22 which is provided with a bore therethrough and a seat 23 which is adapted to engage a portion of the writing cartridge or stylus 24. The point is also shouldered at 22' to engage the casing 10 and draw the bushing 13 into its tapered end.

To the upper end of the lower section 14 there is affixed a hexagonal shaped socket 25. This socket is adapted to receive a male hexagonal plug 26 which is affixed to the lower end of the upper section 27 of the central tube. This upper section 27 is provided with a boss 28 having a helical slot 28' and a threaded portion 29 which is adapted to receive the threaded cap 30 of the writing cartridge 24, the writing cartridge 24 being frictionally received in the cap 30 as at 31. An outer sleeve 32 surrounds the parts just described and has an end portion 32a that frictionally engages the boss 15 so as to rotate therewith. This engagement may be effected by providing serrations on the boss 15 or by other means. The sleeve 32 is provided with helical indentations 33 which, as will be seen by referring to Figures 1 and 4, are adapted to mate with the helical slot 28' in boss 28. Surrounding the sleeve 32 is an outer boss 34 which is adapted to frictionally engage the cap 11 but rotate freely within the casing 10. It will thus be seen that when the cap 11 is rotated relative to the main casing 10, the sleeve 32 will rotate relative to the central tube 14, 27 which is held fixed in the point assembly 13, 22. This action will move the section 27 and the writing instrument 24 longitudinally of the entire casing, the hexagonal means 25, 26 sliding one within the other. As has been described, the tensioning spring 18 provides friction between the bushing 13 and the central tube section 14 so that a certain force must be applied to rotate the section 14 relative to boss 15. This resistance is transmitted to section 27 through coupling 25, 26 so that once the writing instrument 24 has been extracted or retracted to a certain position, it will tend to remain there without the provision of any external means and under normal writing pressure will not retract into the casing.

I claim:

1. In a writing instrument, a propelling mechanism comprising a central tube in two sections disposed longitudinally of each other, means keying said sections together for sliding movement therebetween and common rotary movement, a sleeve surrounding said sections having helical thread means on said sleeve, helical thread means on one of said sections, said thread means engaging one another, a writing stylus coupled to one of said sections and said other tube section having an abutment, a boss surrounding said other section yieldingly urged against said abutment, said sleeve coupled to said boss to prevent relative longitudinal movement relative to said one of said sections, and means to rotate said central tube relative to said sleeve to slide said one of said sections relative to the other thereby extracting or retracting said stylus.

2. In a writing instrument as in claim 1 wherein said keying means comprises a female hexagonal socket a fixed to one section and a male hexagonal plug affixed to the other section.

3. In a writing instrument as in claim 1 wherein said helical thread means comprises a helical slot formed in one of said sections and a helical projection extending inwardly from said sleeve.

4. A writing instrument having a casing in two parts

that are adapted for relative rotation, a point assembly having a bore therethrough secured in one of said parts, a central tube in two sections disposed longitudinally of each other, means keying said sections together for sliding movement therebetween and common rotary movement, one of said tube sections being secured to said point assembly, said one of said tube sections carrying a boss that is yieldingly urged against said point assembly, the other of said tube sections carrying a helical thread, a sleeve surrounding said tube sections and coupled to said boss to prevent longitudinal movement relative to said one of said tube sections, helical thread means on said sleeve, said sleeve thread means engaging the thread means on said other tube section, said other part of said casing being coupled to said sleeve and a writing cartridge coupled to said other of said tube sections and extending within said central tube and the bore in said point

5 assembly whereupon relative rotation between the two parts of said casing expels or repels said cartridge.

5. A writing instrument as in claim 4 wherein said keying means comprises a female hexagonal socket affixed to one section and a male hexagonal plug affixed to the other section.
